US00D994477S

(12) **United States Design Patent** (10) **Patent No.:** **US D994,477 S**
(45) **Date of Patent:** **** Aug. 8, 2023**

(54) **BRACKET APPLIED TO A WINDOW TREATMENT**

(71) Applicant: **Lutron Technology Company LLC**, Coopersburg, PA (US)

(72) Inventors: **Mailing Ren Wu**, Lansdale, PA (US); **Margaret A. Block**, Allentown, PA (US); **David A. Kirby**, Zionsville, PA (US); **Vladislav Pejic**, Allentown, PA (US)

(73) Assignee: **Lutron Technology Company LLC**, Coopersburg, PA (US)

(**) Term: **15 Years**

(21) Appl. No.: **29/847,596**

(22) Filed: **Jul. 26, 2022**

Related U.S. Application Data

(63) Continuation of application No. 29/772,085, filed on Feb. 26, 2021, now Pat. No. Des. 962,043.

(57) **CLAIM**

The ornamental design for a bracket applied to a window treatment, as shown and described.

DESCRIPTION

FIG. 1 is a perspective view of a bracket applied to a window treatment showing our design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a perspective view thereof in an alternate position;

FIG. 10 is another perspective view thereof;

FIG. 11 is a front view thereof;

FIG. 12 is a rear view thereof;

FIG. 13 is a left side view thereof;

FIG. 14 is a right side view thereof;

FIG. 15 is a top view thereof; and,

FIG. 16 is a bottom view thereof.

The broken lines illustrate structure or features which form no part of the claimed design.

1 Claim, 8 Drawing Sheets
